UNITED STATES PATENT OFFICE

134,731

DESIGN FOR A TEXTILE FABRIC

John Howes Burton, East Islip, N. Y., assignor to
Burton Brothers & Co., Inc., New York, N. Y.,
a corporation of New York

Application July 4, 1942, Serial No. 107,427

Term of patent 3½ years

To all whom it may concern:

Be it known that I, John Howes Burton, a citizen of the United States and a resident of East Islip, county of Suffolk, and State of New York, have invented a new, original, and ornamental Design for a Textile Fabric, of which the following is a specification, reference being had to the accompanying drawing forming part thereof.

The figure is a plan view of a textile fabric embodying my design.

I claim:

The ornamental design for a textile fabric, as shown.

JOHN HOWES BURTON.
